APPARATUS FOR MANUFACTURING PRE-STRESSED CONCRETE MEMBERS

Ben C. Gerwick, Jr., Oakland, Calif., assignor to Ben C. Gerwick, Inc., San Francisco, Calif., a corporation of California

Filed Feb. 25, 1957, Ser. No. 642,124

4 Claims. (Cl. 25—118)

This invention relates generally to the manufacture of reinforced concrete beams, and particularly to beams provided with pretensioned reinforcing members.

The construction industry has recognized the advantages of concrete beams and like structural members that are prestressed. The desirability of prestressing by employing deflected tensioned reinforcement has also been recognized, particularly as applied to relatively long beams. However many problems have been encountered which have prevented wide commercial use. The post tensioning method has been attempted for this purpose, but has not been successful, due largely to its inherent limitations and lack of positive control. In certain instances long beams having deflected pretensioned strands have been produced, but the cost has been uneconomical, and the equipment employed has been elaborate and expensive to install and operate. Relatively crude equipment has been proposed, which is provided with a jack for deflecting a pretensioned strand at one point in a form, but this has not been suitable for large scale operations.

In general, it is an object of the present invention to provide apparatus which makes possible large scale manufacture of concrete beams having pretensioned and deflected reinforcement.

Another object of the invention is to provide apparatus of the above character which can be readily set up for beam casting operations, and which accommodates contraction of the beam after the concrete has hardened.

Another object of the invention is to provide apparatus of the above character which permits considerable flexibility and adjustment with respect to the size, shape and type of concrete member being made, and with respect to the pattern and extent of deflection of the reinforcing strands.

Additional objects and features of the invention will appear from the following description in which the preferred embodiments have been set forth in detail in conjunction with the accompanying drawing.

Referring to the drawing:

FIGURE 1 is a plane view schematically illustrating apparatus incorporating the present invention.

FIGURE 2 is a side elevational view of the apparatus shown in FIGURE 1 with three harping units being applied to deflect the reinforcing strands.

FIGURE 3 is a cross sectional view on an enlarged scale taken along the line 3—3 of FIGURE 1, and showing the construction of one of the harping units.

FIGURE 4 is a cross sectional detail taken along the line 4—4 of FIGURE 3.

FIGURE 5 is an enlarged detail in section illustrating the attachment between the deflecting yokes or forks and the pull cable.

FIGURE 6 is a view taken along the line 6—6 of FIGURE 5.

FIGURE 7 is a side elevational view partly in section, illustrating a longer pull rod for making connection with one of the cable engaging forks.

FIGURE 8 is a side elevational view similar to FIGURE 3 but showing a modified type of harping unit.

FIGURE 9 is a cross sectional view taken along the line 9—9 of FIGURE 8.

2

FIGURE 10 is a cross sectional view taken along the line 10—10 of FIGURE 8.

The present invention employs rigid means forming a horizontal working bed, and which serves to carry one or more forms for pouring a beam of the desired contour. Horizontally spaced means are provided for engaging and positioning reinforcing members at locations corresponding generally to the ends of the beam being cast. A plurality of harping units are associated with the bed and serve to engage and apply force to the reinforcing members whereby they are deflected downwardly to the desired extent to produce the desired curvature. Preferably the reinforcing members are engaged in at least three points, whereby the curve obtained approximates a parabola. Each of the harping units is of special construction as will be presently described.

Referring to the drawing, the rigid bed 10 has a length somewhat greater than the longest beam which is to be manufactured. In some instances this bed may be of such length as to permit casting a series of beams simultaneously. In practice the bed may consist of structural steel members 11, having suitable anchorage to the ground. Adjacent the ends of the bed suitable means are provided for anchoring the reinforcing members and for applying suitable tension. In FIGURE 1 one anchoring means is indicated schematically at 12, and can consist of a rigid member through which the ends of the reinforcing members extend, and to which they are anchored. This member in turn is rigidly mounted upon the bed. At the other end of the bed the reinforcing members extend through the member 13, which is likewise rigidly anchored to the bed. Suitable jacking means 14, as for example of the hydraulic type, is attached to the ends of the strands to apply the desired tension.

Various types of molding or casting forms can be positioned upon the bed, depending upon the contour of the concrete member desired. As illustrated in FIGURE 3, the mold can consist of a bottom horizontal soffit board 15 together with the side walls 17, which are hinged at 18. End closure plates 21 can be provided with suitable perforations to receive the reinforcing strands. Distribution of the perforations determines the distribution pattern of the beam. Near the ends of the form it is desirable to provide additional means for supporting the reinforcing members at a desired level. This means can be in the form of a standard 22 formed to provide vertically spaced horizontal supporting rods. These rods engage and support the cables at the desired levels.

Each of the harping units for engaging the reinforcing members consists of a device located within the casting form, together with means exterior of the form for applying downward deflection force. Thus referring particularly to FIGURES 3—8 each harping unit consists of a yoke-like member 26 having its lower end attached to the rod-like member 27. Apertures in the side of the yoke carry the removable rods 28 for engaging the reinforcing strands. By turning the member 27, it can be disengaged with respect to the nut 29 and thus detached from the yoke. In the modification of FIGURE 7 the member 27a is of extended length and in the form of a polished and tapered rod as illustrated, to permit its removal from the hardened concrete. The lower end of member 27 (or 27a) is pivotally connected to a half sheave or saddle 32 which is engaged by the looped cable 33.

A structural frame 36 extends laterally of the working bed, and carries the bearings 37 for journaling the roller 38. This roller is provided with grooves 35 adapted to be engaged by the two lengths of the cable 33. The ends of the cable are attached to a head 40, which is slidably guided within the frame. A rod 39 is attached to the head and extends from one end of the frame, where it is

threaded and provided with nut 41. By turning nut 41, it is evident that the rod 39 can be drawn to the left as viewed in FIGURE 3, thus applying pull to the cable 33, and pulling downwardly upon the yoke 26.

In FIGURE 1 three harping units of the type described above have been distributed along the length of the bed. Generally it is desirable to locate one unit with a short rod 27 midway between the ends of the form, together with two or more additional harping units with the large rods 27a for deflecting the reinforcing members at one or more points between the midpoint and the ends of the beam. In some instances a single unit is sufficient.

Operation of my apparatus is as follows: The standards 22 are located on the working bed in accordance with the length of the beam. Cables are threaded with respect to the anchoring and tensioning means, and through the standards 22. Also the cables are threaded through the end plates 21 of the form. The harping units are located between the standards 22 in accordance with the extent and curvature of the desired deflection. The rods 28 of the yokes are engaged with the several strands and the yokes 26 attached to the rods 27 and 27a. The strands of the reinforcement are tensioned a predetermined amount by the means 14. In some instances the amount of tension applied at this point to the various strands may vary to a predetermined degree in accordance with the positioning of the strands in the final beam and the extent of deflection to follow. It may be mentioned at this point that tensioning before deflection is carried out to such an extent that after deflection the tension is within the limits desired.

Following the operation outlined above, the harping units are caused to pull downwardly upon the cables to secure the desired degree of deflection. This is accomplished by turning the nuts 41 to pull the cables 33 and thus pull the yokes 26 downwardly the desired amount. After deflection to the desired extent, the side walls of the form are applied and the wet concrete mix is introduced. Vibration and like techniques are applied to properly compact the concrete. After the concrete has hardened, the jacking means is relaxed and the strands at the ends of the beam are severed as by cutting or burning. Release of tension is accompanied by a substantial amount of end-wise contraction of the beam, which is accommodated by the harping units because of the cables 33 which provide articulated connections that accommodate a substantial amount of movement of the members 27, 27a longitudinally of the bed. Cables 33 are maintained tensioned until after releasing the tension of the reinforcing strands, thereby retaining the beam to prevent lateral bowing. Then the tension on these cables is released and the cables are disengaged from the rods 27, 27a by pulling the pins of the sheaves 32, and thereafter rotating the members 27, 27a to disengage them from the yokes 26. The holes left by the members 27, 27a are filled by suitable grouting. Instead of using such rod-like members, less expensive pull rods can be used which can be left in the beam.

It will be evident from the foregoing that I have provided apparatus which will permit a predetermined amount of deflection of the reinforcement to obtain the curvature desired. The harping units can be quickly set up for successive casting operations, and readily disengaged after the concrete has hardened and the reinforcing strands released. Because of the ease with which multiple harping units can be applied and operated, it is a simple matter to deflect a plurality of strands to a vertical curvature that closely approximates the theoretical optimum. The harping units are not injured by sudden contraction of the beam when tension on the reinforcement is relieved. In addition to the foregoing the apparatus is relatively flexible with respect to the sizes and types of beams which can be made. Reinforce-

ment can be located in accordance with any desired distribution pattern and all of the strands simultaneously deflected to the extent desired.

The harping means shown in FIGURES 8-10 consists of a frame 46, similar to frame 36, and serving to mount the shaft 47. Two sheaves 48 on shaft 47 are engaged by the pull cable 49. The ends of the cable are attached to a cross head 51 which has threaded engagement with rod 52 and is slidably guided within the frame. A gear 53 is secured to the outer end of rod 52 and is engaged by the pinion 54 on shaft 55. By turning this shaft, as by means of a portable pneumatic motor, the nut 51 and the cable 49 can be moved a desired amount. The looped end of the cable is shown engaging a half sheave 56 or saddle on the lower end of the yoke or fork 57.

In the foregoing I have described my apparatus as being used for casting beams one at a time. For large scale production it is desirable to employ a bed of sufficient length for casting two or more beams simultaneously. In such event the forms are aligned lengthwise, with a space between adjacent ends. Standards 22 are provided between forms and at the remote ends. Each form is provided with end closures 21. The strands are threaded through the forms, the end closures 21 and the standards 22. At one end of the bed the strands are anchored, and at the other end they may be connected to tensioning means. The harping units are applied whereby the desired number of units are provided for each form. After the strands have been tensioned, the harping units are operated to obtain the desired amount of deflection. Casting and release of the strands and harping units proceeds are previously described. The greater longitudinal movement of the beam in this instance, upon releasing the strands, is accommodated by the harping units.

I claim:

1. Apparatus for the manufacture of prestressed concrete beams, comprising a beam casting form, at least one elongate concrete reinforcement member supported within said form, at least one deflecting member located within said form and engaging each reinforcement member intermediate the ends thereof, a frame located adjacent said form, a cross head associated with each deflecting member slidably mounted within said frame, a screw shaft associated with each cross head, each screw shaft being mounted on said frame and being adapted to produce sliding movement of the corresponding cross head, cable means operatively connecting each cross head with the corresponding deflecting member, and roller means journaled within said frame adapted to guide movement of said cable means in a predetermined direction, whereby sliding movement of each cross head will produce bowing in the predetermined direction of each reinforcement member.

2. A device for deflecting a plurality of longitudinally tensioned strands in concrete beam forming apparatus, said device comprising a strand deflecting unit engaged with the strands, means for applying a force to said strand deflecting unit, and means connected between said strand deflecting unit and said force-applying means to transmit applied force to said deflecting unit in a direction substantially perpendicular thereto, said connecting and force-transmitting means including a rod having a tapered portion with its small end releasably secured to said deflecting unit, and further including an articulated connection between the large end of said rod and said force-applying means, said articulated connection accommodating beam movement occurring when tension on the strands is released, and said rod being releasable from said strand deflecting unit to permit the force-applying means and the connecting and force-transmitting means to be disconnected from said unit.

3. Apparatus for deflecting strands in a prestressed concrete beam form, comprising a strand engaging unit en-

gaged with the strands, a rod having one end connected to said strand engaging unit and the other end projecting through an opening in said form, a saddle, a flexible cable having a bight thereof trained about said saddle, force exerting means connected to the ends of said flexible cable for exerting a pull upon the cable and said saddle, and a pin releasably and pivotally connecting the saddle to the rod exteriorly of the form to enable the cable-engaged saddle to be disconnected from said rod and thereby permit removal of the beam from the form.

4. Apparatus for deflecting strands in an elongated pre-stressed concrete beam form wherein the ends of the strands are adjacent the ends of the form, comprising a strand engaging unit engaged with the strands between the anchored ends thereof, a rod having one end connected to said strand engaging unit and the other end projecting downwardly through an opening in said form, a saddle, a pivot pin releasably and pivotally connecting the saddle to said other end of said rod, a flexible cable trained

around said saddle, and means connected to said flexible cable for exerting a pull thereon and upon the strand engaging unit to deflect the strands within the form to a predetermined extent.
